UNITED STATES PATENT OFFICE.

HALVOR OLSON, OF BELVIEW, MINNESOTA.

PLANE ATTACHMENT FOR HANDSAWS.

1,324,922.

Specification of Letters Patent. Patented Dec. 16, 1919.

Application filed June 19, 1919. Serial No. 305,350.

To all whom it may concern:

Be it known that I, HALVOR OLSON, a citizen of the United States, residing at Belview, in the county of Redwood and State 5 of Minnesota, have invented certain new and useful Improvements in Plane Attachments for Handsaws; and I do hereby declare the following to be a full, clear, and exact description of the invention, such as will enable others skilled in the art to which it 10 appertains to make and use the same.

My invention has for its object to provide a plane attachment for hand-saws; and, to this end, it consists of the novel devices 15 and combinations of devices hereinafter described and defined in the claims.

In the accompanying drawings, which illustrate the invention, like characters indicate like parts throughout the several 20 views.

Referring to the drawings:—

Figure 1 is a fragmentary right side elevation of a hand-saw having the plane attachment secured to the handle thereof; and 25 Fig. 2 is a detail view in section taken on the line 2—2 of Fig. 1.

The numeral 3 indicates the blade of a hand-saw and the numeral 4 indicates the handle thereof. In the upper edge portion 30 of the handle 4, is a shoulder 5 which is oblique to the back of the saw, and forward of this shoulder 5, said handle is provided with an L-shaped notch to afford bearing surfaces 6 and 7, the former of which extends substantially parallel to the back of 35 the saw and the latter of which, like the shoulder 5, extends oblique to said back. At the intersection of the bearing surfaces 6 and 7, the handle 4 is further provided 40 with a forwardly projecting slot 8. It will be noted that the bearing surface 6 extends from the outer end portion of the shoulder 5 to the inner end portion of the shoulder 7 and continues into the slot 8.

45 The plane 9, which, as shown, is of the block type, has, in its right side and forward end portion, a channel 10, the flanges of which embrace the sides of the saw handle 4 and the contour of the bottom of said 50 channel is such as to closely engage the shoulder 5, bearing surfaces 6 and 7 and outer edge portion of the handle 4, forward of the bearing surface 7. A web 11, inter-

gral with the body of the plane and the flanges of its channel 10, extends into the 55 slot 8 and forms a continuation of the forward end portion of the bearing surface 6. To detachably secure the plane 9 to the handle 4, a bolt 12 is extended through a bore in the outer flange of the channel 10 60 and an alined bore in said handle, and has screw-threaded engagement with the inner flange of said channel.

The iron 13 of the plane 9 is adjusted by a pinion 14 journaled in bearings 15 on the 65 bottom of said plane and meshes with rack teeth 16 in the back of said iron. The shaft of the pinion 14 extends through the outer side of the plane 9 and is provided with a head or thumb-piece 17 in which is formed 70 a notch, thus permitting said pinion to be turned by hand, a screw-driver or other tool.

From the above description, it is evident that, by the interlocking engagement of the 75 plane with the saw handle and the bolt 12, said plane is securely and firmly attached to the saw handle, so that the plane may be operated by said handle. The attachment is especially adapted for smoothing 80 the end of a board, after the same has been cut by the saw and avoids the necessity of carrying an independent plane. As is well known, carpenters working on scaffolding or in other inconvenient places, find it difficult to use independent tools as they are liable to drop the ones not in use, being 85 unable to find a safe place to lay the same.

What I claim is:—

1. The combination with a hand-saw, of a 90 plane detachably secured at one of its sides to the upper edge portion of the handle of the saw, and means at the other side of the plane for adjusting the iron thereof.

2. The combination with a hand-saw, of a 95 plane having in one of its sides a channel into which the upper edge portion of the handle of the saw extends, and a bolt extending through the flanges of said channel and the handle of the saw to detachably 100 secure the plane thereto.

3. The combination with a hand-saw, of a 105 plane having in one of its sides a channel into which the upper edge portion of the handle of the saw extends, said channel having an offset portion arranged to engage

a shoulder on said handle, and means detachably securing the plane to the handle of the saw.

4. The combination with a hand-saw, of a plane having in one of its sides a channel into which the upper edge portion of the handle of the saw extends, said channel having an offset portion arranged to engage a shoulder on said handle, a web extending 10 into said channel and arranged to enter a

correspondingly formed slot in the handle of the saw, and means detachably securing the plane to said handle.

In testimony whereof I affix my signature in presence of two witnesses.

HALVOR OLSON.
